B. F. LEWIS.
DOOR OPERATING MECHANISM.
APPLICATION FILED JULY 31, 1916.

Patented Mar. 26, 1918.

BENJAMIN F. LEWIS.
INVENTOR.

BY *William A. Hirtle*

ATTORNEY.

UNITED STATES PATENT OFFICE.

BENJAMIN F. LEWIS, OF PITTSBURGH, PENNSYLVANIA, ASSIGNOR OF ONE-FOURTH TO JOHN LINZ AND ONE-FOURTH TO GEORGE LINZ, BOTH OF PITTSBURGH, PENNSYLVANIA.

DOOR-OPERATING MECHANISM.

1,260,782.

Specification of Letters Patent.

Patented Mar. 26, 1918.

Application filed July 31, 1916. Serial No. 112,279.

To all whom it may concern:

Be it known that I, BENJAMIN F. LEWIS, a citizen of the United States, residing at Pittsburgh, in the county of Allegheny and 5 State of Pennsylvania, have invented certain new and useful Improvements in Door-Operating Mechanisms, of which the following is a specification.

The present invention relates to improvements in door operating mechanisms, and is particularly useful for motor vehicles and carriages, in which the chauffeur or driver can by means of my invention, open and close the doors of said vehicle without leaving his seat. The device is useful and desirable in connection with taxi-cabs, as the chauffeur can in inclement weather open and close the doors for his passengers, without leaving his position at the steering wheel 10 and operating parts of the cab.

Another feature of my invention is that it can be used by making minor changes in the present construction of automobiles, the usual locks on the doors being used with my 15 invention. The parts of the invention which operate the spring tongue of the ordinary lock being located between the outer and inner side walls of the car body, as will be hereinafter explained in this specification, and in a position which does not interfere with the door itself, the slideable window sometimes used in the door, can be used, same sliding downward into and between the outer and inner walls of the door 20 body as usual.

In the accompanying drawings forming part of this specification I have illustrated one complete example of the physical embodiment of my invention, constructed according to the best mode I have so far devised for the practical application of the principles of the invention.

Figure 1 is a vertical section through the vehicle body taken on line 4—4 of Fig. 7 45 showing parts of my invention in position.

Fig. 2 is an enlarged fragmentary horizontal cross-section through the vehicle body taken on line 3—3 of Fig. 7.

Fig. 3 is a vertical elevation on line 5—5 50 of Fig. 7.

Fig. 4 is a plan view of two operating parts of my invention, taken on line 6—6 of Fig. 1.

Fig. 5 is a vertical cross-section taken

through a part of my device on line 7—7 55 Fig. 4.

Fig. 6 is a section taken on line 8—8 of Fig. 4.

Fig. 7 is a vertical longitudinal section taken on line 1—1 of Fig. 8, showing my invention in operative position in an automobile. 60

Fig. 8 is a horizontal section of same taken on line 2—2 of Fig. 7.

Fig. 9 is a detail horizontal section of 65 part of the device taken on line 9—9 of Fig. 7.

Fig. 10 is a section on line 10—10 of Fig. 8, showing details of a portion of a gear and lever forming part of the invention. 70

Fig. 11 is a horizontal section taken on line 11—11 of Fig. 10.

Referring to the drawings the numeral 1 indicates the body of a vehicle, having the usual outer and inner side walls 2, 3, and 75 floor 4. The door 5 has inner and outer walls 6, 7 and hinges 8, 9 attaching it to the vehicle body 1. 10 indicates a transverse shaft or rod fastened preferably to the under side of the floor 4 at points 11, 12. The said 80 shaft 10 carries an adjustable part 13, having two projecting treads 15, 16, and a locking screw 14 to lock 13 at any desired point on the shaft. Shaft 10 carries bevel gear 17, which meshes into bevel gear 18 on the 85 longitudinal shaft 19. The latter shaft 19 is supported at 20, 21 to the under side of the floor 4. Shaft 19 carries at its rear end a gear 22 which meshes into the teeth on 90 the under side of the arc plate 23. The arc plate 23 has a bearing at 24, supported by bent plate 25 attached to the under side of the floor at 26. A bent lever arm 27 is mounted on the uppermost end of the axle 28 forming part of the arc plate 23, but is 95 free to rotate thereon. The lever arm 27 has a downwardly disposed projection 29, which passes through a slot 30 in the arc plate 23 for a purpose described below.

The free end 31 of lever 27 is bent upwardly 100 substantially at right angles, and is slidably attached to a rod 32, the latter being mounted on the inner face of the outer partition 6 of the door 5, at points 33, 34. 35 shows the door 5 when thrown wide open by the device.

Shaft 19 carries an adjustable disk 36, shown in Figs. 4 and 6 in larger detail,

which has a depression 37, on the face of the same, to receive the tongue 38, forming part of the bent end 39 of vertical lever 40.

An adjusting and locking screw 41 is 5 provided to lock the loose disk 36 at any desired point on the shaft 19. Lever 40 is fulcrumed at 42 in a bracket 43, see Fig. 9, attached to the wall 44 of the vehicle body 1. Lever 40 at its lower end operates against 10 a spring 45 carried on a pin 46, the latter being supported by a part 47, located between the walls 2, 3 of the vehicle body, so that lever 40 is always in contact with the face of disk 36, due to the constant pressure 15 of the spring 45.

The upper end of the lever 40 is round in shape, and bears at 48 against a loose part or block of T cross-sectional shape, (see Fig. 3), the latter being carried slidably in a 20 casing 50 attached by flanges 51 and 52 to the wall 44 before mentioned. T-block 49 engages directly against the tongue 53 of the ordinary lock 54 used in situations of this character on automobile doors. The 25 tongue 53 it will be noted protruding from the lock 54 is spring actuated from within the lock, and is normally in extended position and in engagement with casing 50, thereby holding the door closed with relation to the vehicle body 1. In this position of 30 53, the lever 40 occupies a substantially vertical position, due to the action of the spring 45, tending to throw the lower end 55, and extension 38 into contact with the indented portion 37, of disk 36, when the latter is in proper position on shaft 19, and 36 is adjusted and set on said shaft so that 35 this is possible, and locked by 41 thereon.

The edge 56 of 38 is as shown in Fig. 5 40 rounded to present a smooth surface of as small frictional area as possible, when in engagement with the depression 37 of disk 36.

When disk 36 revolves it is seen that 38 45 will be thrown to the left as seen in Fig. 7, the upper end 48 of lever 40 thereby moving toward the right, as also part 49, and tongue 53 of the lock 54. In this fashion 53 is pressed back flush with 57 of the door 50 and thereby allowing the latter to be opened when operated by lever 27 as will be further explained.

If the tread 15 is now pressed forward to the left, see Fig. 8, the bevel gears 17, 18 55 operate, and shaft 19 will revolve as indicated by arrow Fig. 6, in which event disk 36 revolves, and allows door 5 to be opened as above described. As shaft 19 revolves, gear 22 operates arc plate 23, which last 60 engages against projection 29 of lever 27, thereby revolving 27 about central axle 28, and opening door 5 to position 35, upturned projection 31 sliding on rod 32 during the operation. The purpose of the slot 30 in the 65 arc plate 23 is to provide a small amount

of "lost motion", before the lever 27 comes into action. That is to say that as shaft 19 starts to revolve, the arc plate 23 turns a short distance, practically the length of the slot 30, in a rotary direction, before the projection 29 engages against the edge of the slot 30, thereby allowing time for 36 and 40 to operate and place tongue 53 in withdrawn position, before the lever 27 starts to open the door. 75

It is evident that when the part 13 is thrown backward by using tread 16 as seen in Fig. 8 that the reverse operation will take place, and the door 5 will be retracted by lever 27, 53 engaging 50, thereby locking the door shut. In closing the door the spring pressed tongue 53, as is usual has a rounded shape at 58 either concave or convex, and as it engages against the side wall 44, it is readily depressed into withdrawn 85 position, and allows the door to be fully closed by lever 27.

It is to be noted further that the ordinary handle 59 of lock 54, shown dotted in Fig. 7 can be used to open the door and close same, 90 when it is desired to use it in the ordinary manner, without derangement of any of the parts of this invention.

A hand lever 60 shown dotted in Fig. 7 can be used to operate the shaft 10 as is 95 readily seen, and thereby operate the door in similar fashion to that described above.

As the operating parts are practically attached only to the lower portion of the door 5, any window that may be in any particular type of vehicle, positioned slidably in the door, may still be used without alterations of the vehicle, and as for the most part the device is inclosed between the walls of the vehicle, and under the floor of same, it 100 can be applied to the ordinary type of automobile successfully, by making minor 105 changes and additions to same. This advantage will be readily appreciated.

What I claim is:—

1. In a door operating mechanism, a pivotally mounted door, a rotatable arc plate gear having a slot and mounted independently from said door, a lever rotatably mounted on the said gear, having on one end thereof a downwardly disposed lug projecting into said slot, and on its opposite end an upturned projection; a horizontally disposed rod attached to said door slidably engaging the upturned projection, and means for rotating said arc plate gear to operate the aforesaid door. 110

2. In a door operating mechanism, a hinged door, a rotatable arc plate gear having a slot and mounted independently from said door, a lever rotatably mounted on said gear, having on one end thereof a downwardly disposed lug projecting into said slot, and on its opposite end an upturned projection, a horizontally disposed rod at- 115 130

tached to said door slidably engaging the upturned projection, a door lock releasing means, means for rotating the arc plate gear and engaging the lock releasing means, to 5 operate the aforesaid door.

3. In a door operating mechanism, a shaft having a gear on one end, an arc plate gear provided with a slot, meshing with the first mentioned gear, a support and bearing for 10 said arc plate gear, a bent lever rotatably mounted on the arc plate gear having on one end thereof a downwardly disposed lug projecting into said slot, and on its opposite end an upturned projection, a horizontally 15 disposed rod attached to the said door slidably engaging said upturned projection of the bent lever, a door lock releasing means, means on the shaft engaging the lock releasing means, and means for rotating the 20 aforesaid shaft to operate said door.

4. In a door operating mechanism, a shaft having a gear at one end, an arc plate gear provided with a slot, meshing with the first named gear, a support and bearing for said

arc plate gear, a bent lever rotatably mounted on the axis of the arc plate gear, having on one end thereof a downwardly disposed lug projecting into said slot, and on its opposite end an upturned projection, a horizontally 25 disposed rod attached to the said door 30 slidably engaging the upturned projection of the bent lever, a door lock releasing means, means on the shaft engaging the lock releasing means, a bevel gear on the forward end of the aforesaid shaft, a transverse shaft 35 having a bevel gear thereon engaging first named bevel gear, and a tread casting adjustably mounted on the transverse shaft, the whole mechanism being designed to unlock and operate the aforesaid door from a 40 remote point.

In testimony whereof I affix my signature in the presence of two witnesses.

BENJAMIN F. LEWIS.
